UNITED STATES PATENT OFFICE.

CHARLES W. BAILEY, OF PHILADELPHIA, PENNSYLVANIA.

DESIGN FOR A BADGE.

SPECIFICATION forming part of Design No. 31,114, dated July 4, 1899.

Application filed June 10, 1899. Serial No. 720,094. Term of patent 14 years.

To all whom it may concern:

Be it known that I, CHARLES W. BAILEY, a citizen of the United States, residing in the city and county of Philadelphia, State of Pennsylvania, have invented and produced a new and original Design for a Badge, of which the following is a specification, reference being had to the accompanying drawings, forming part thereof.

10 The leading feature of my design for a badge is a cross-shaped figure, the representation of an eagle, a chain with broken shackles in the talons of the eagle, a central field, and a shield in the latter.

15 Figure 1 represents a view of the obverse of a badge embodying my design. Fig. 2 represents a view of the reverse thereof.

In the drawings, A designates a badge con-

sisting of a cross-shaped figure B, the upper limb of which is surmounted by the representation of an eagle C. In the talons of the latter is the chain D, with broken shackles E thereon. In the center of the figure B is the field F, in which is the shield G, composed of the representation of a bastion H, a landscape J, inclosed by the latter, and rays K between said bastion and landscape.

Having described my invention, what I claim as new, and desire to secure by Letters Patent, is—

The design for a badge substantially as shown and described.

CHAS. W. BAILEY.
